UNITED STATES PATENT OFFICE.

WILLIAM H. POND, OF PROVIDENCE, RHODE ISLAND, ASSIGNOR TO THEODORE W. FOSTER & BRO. CO., OF PROVIDENCE, RHODE ISLAND, A CORPORATION OF MAINE.

LACQUERING MACHINE.

Application filed September 7, 1922. Serial No. 586,692.

To all whom it may concern:

Be it known that I, WILLIAM H. POND, a citizen of the United States, residing at Providence, in the county of Providence and State of Rhode Island, have invented 5 certain new and useful Improvements in Lacquering Machines, of which the following is a specification.

This invention relates to improvements in 10 machines for applying a coating of lacquer or other liquid covering to work, and the object of this invention is to provide a carrier for the work adapted to immerse the work in a bath of liquid lacquer or other 15 liquid covering, means also being provided for lifting the work from the bath at a very slow speed, the lifting mechanism being automatically arrested in its action when the work has been removed from the bath. 20 A further object of this invention is to construct a machine of this character with a plurality of units each adapted to be independently operated to immerse the work and when the work has been lifted from 25 the bath to automatically stop, permitting it to be removed, and fresh work to be applied to the carrier.

With these and other objects in view, the invention consists of certain novel features 30 of construction, as will be more fully described, and particularly pointed out in the appended claims.

In the accompanying drawings:

Figure 1 is a side elevation of my machine 35 showing one of the bath tanks in section and some of the others broken away to better illustrate the operating mechanism.

Figure 2 is a plan view of the machine.

Figure 3 is a sectional elevation on line 40 3—3 of Figure 4, showing the power transmitting member.

Figure 4 is a side elevation of the power transmitting member.

Figure 5, is a plan view showing one of 45 the units as disconnected from the others.

Figure 6 is a side elevation of one of the operating units.

It is found of advantage in lacquer applying machines to provide a bath tank for 50 carrying the lacquer and to provide a rack for carrying the work adapted to be immersed in the tank and to flexibly connect a lifting device, whereby the work may be lifted at a very slow speed, or a speed at which 55 the lacquer is adapted to dry upon the work

as it is being lifted from its bath thereby effectually preventing the lacquer from dripping from the work and so leaving bad places thereon, which would be the case if it were quickly withdrawn from the bath 60 and the following is a detailed description of one construction of machine by which these results may be successfully accomplished.

With reference to the drawings, 10 designates the frame of the machine which may be made of suitable material and on which the operating mechanism is mounted. I preferably form the machine of a length 65 sufficient to mount and operate a plurality 70 of work carrying units so that each unit may be operated independently of the others, whereby when one is being loaded with fresh work and the work lowered into the bath it does not affect the action of the others and 75 a sufficient number of such units may be employed in a single machine to keep one attendant busy, the mechanism being set so that the units may be operated successively 80 if desired.

In the construction of the machine I preferably provide a separate tank 11 for each separate unit, instead of using one elongated tank for all of the units, I then construct a rack or carrier 12 on which the work 13, illustrated in dotted lines, may be mounted by any suitable means, and in order to lift this carrier with its work from the tank at a very slow speed, I have provided a drum or pulley 14, which is mounted to rotate 85 on a fixed shaft 15 and which drum or pulley is connected to the carrier by the flexible band or connector 16 which may be a chain, belt or other suitable band. Also, on this shaft 15, I have mounted a similar pulley 90 or drum 17, which is connected to the pulley 14, and over which a flexible band 18 is passed with a weight 19 connected to its end, which weight is heavy enough to counterbalance the work carrier when loaded. 100

In order to drive this lifting drum or pulley at a very slow speed, I have provided a main driving shaft 20, which may be driven from a belt, not shown, through the pulley 21 to transmit its power through the pulley 22, belt 23 and large pulley 24 to the jack shaft 25, which shaft transmits its motion through the gear 26 to the gear 27 on the short shaft 28 which latter shaft in turn transmits motion through the gear 29 to the 105 119

gear 30 on the gear shaft 31, and motion is transmitted from this shaft through the gear 32 to the gear 33 on the main power transmitting shaft 34, whereby this latter shaft 5 is driven at a very slow rate of speed to drive the different lifting mechanisms.

At intervals along this power transmitting shaft, I have mounted a plurality of friction driving discs 35, each being adapted to 10 transmit its power to the lifting drum or pulley of the different units above described, and in order to control the transmission of this power from these discs 35 to these pulleys or drums 36, I have pivotally mounted 15 a shaft 37 in a yoke 38, which yoke is fixed to the pin 39 to oscillate in the bearing 40, the friction roll 41 being fixed to one end of the shaft 37 to contact with the face of the disc 35, while the friction roll 42 is fixed to 20 the opposite end of this shaft to frictionally engage the side face of the lifting pulley 14, and in order that these friction rolls may engage their respective surfaces with the proper pressure I have fixed an arm 43 on 25 the lower end of pin 39 and to the outer end of this arm I have attached a tension spring 44, which serves to normally press these rolls against their respective driving and driven surfaces.

30 In order to arrest the lifting action of the drum or pulley 14 when the work carrier has lifted his work from the bath, I have mounted a cam or protuberance 45, (see Figures 2 and 5) whereby when the pulley is rotated 35 to a pre-determined point, this cam is moved to engage the friction roll 42, and swing the shaft 37 in its bearings to move the friction roll 41 from contact with its driving disc 35 whereby the rotation of the pulley 14 is 40 arrested.

After the finished work has been removed from its carrier and fresh work is positioned thereon, it is desired to drop the carrier with its work back into the bath and to accomplish this in a simple and effective way, I have connected an operating handle 46 to the end of the lever 43, whereby an endwise pull on this handle further rotates the friction driving member to release the roll 42 from the cam 45, thereby leaving the pulley 14, to be rotated by hand to lower the carrier with its work into the bath, the handle 46 is then released permitting the friction drive to again engage the side face of the pulley 14 and disc 35 to start the lifting operation mechanism again.

In some cases in order to flexibly or yieldably mount the pulley 14 upon its fixed shaft 15, I mount a spring 47 on this shaft to move 60 the pulley laterally and press it against the working face of the roll 42.

By my improved construction it will be seen that any one of the units may be operated entirely independently of the others 65 and when each has lifted its work out of the

bath, it is automatically arrested to wait for the attendant to remove the finished work and apply fresh work thereto, to be subsequently lowered into the bath to be treated, and as each is operated independently of the 70 others and as they are arranged to operate consecutively the attendant has time to change the work on one while the others are still in operation.

The foregoing description is directed solely towards the construction illustrated, but I desire it to be understood that I reserve the privilege of resorting to all the mechanical changes to which the device is susceptible, the invention being defined and limited 80 only by the terms of the appended claims.

I claim:

1. In a machine of the character described, a bath tank, a work carrying rack adapted to be lowered into said tank, means for lifting the rack and its work from the bath at a predetermined speed, driving means therefor and cam means for automatically disconnecting the lifting means from the driving means when the work has 90 been lifted clear of the bath.

2. In a machine of the character described, a bath tank, a work carrier adapted to be immersed with its work in said tank, means for lifting the carrier and work from said 95 bath, means for automatically arresting the lifting motion at a predetermined period, and means whereby the power transmitting mechanism may be disconnected from the lifting mechanism to permit the carrier with 100 its fresh work to be lowered into said bath.

3. In a machine of the character described, a bath tank, a work carrier adapted to be immersed with its work in said tank, a winding drum, a flexible connector between said drum and carrier, means for applying a lifting power to said drum, and means controlled by the winding drum for automatically arresting the lifting action 105 when the work has been lifted from the tank.

4. In a machine of the character described, a bath tank, a work carrier adapted to be immersed with its work in said tank, a winding drum, a flexible connector between said drum and carrier, means for applying a lifting power to said drum, means for automatically arresting the lifting action when the work has been lifted from the tank and manually operable means for disconnecting said power means whereby a 110 fresh supply of work with the carrier may descend by gravity into the tank.

5. In a machine of the character described, a bath tank, a work carrier adapted to be immersed with its work in said tank, 115 a counter weighted winding mechanism, a flexible connector between said carrier and mechanism, driving means for said winder, means in said winder for arresting the action of the driver when the work is raised 120

from the tank, and means for releasing the winder from the driver to again lower the carrier with its work into the tank.

6. In a lacquering machine, a bath tank, a work carrier adapted to be immersed with the work into said tank, a lifting member connected to said carrier, a driving shaft, a pivotally mounted power transmitting member connecting said shaft with said lifter and means for swinging said member on its pivot to disconnect it from the lifter and from the action of the driving shaft.

7. In a lacquering machine, a bath tank, a work carrier adapted to be immersed with the work into said tank, a lifting member connected to said carrier, a driving shaft a pivotally mounted power transmitting member connecting said shaft with said

lifter and means for swinging said member on its pivot to disconnect it from the lifter and from the action of the driving shaft and manually operable means for further swinging said member to release said lifter to be again lowered with work into the tank.

8. In a machine of the character described a plurality of independently operable units each including a bath tank, a work carrying rack adapted to immerse its work in said tank, means whereby each carrier with its work may be lifted independently from its bath at a predetermined speed, and means for automatically arresting the lifting action of each carrier when it has lifted its work from the bath.

In testimony whereof I affix my signature. 35
WILLIAM H. POND
